UNITED STATES PATENT OFFICE.

CHARLES W. COTTEW, OF SHERIDAN, ILLINOIS.

COMBINATION PORTABLE ELEVATOR AND WAGON-DUMP.

1,075,196.

Specification of Letters Patent.

Patented Oct. 7, 1913.

Application filed April 29, 1908, Serial No. 423,291. Renewed February 15, 1913. Serial No. 749,061.

To all whom it may concern:

Be it known that I, CHARLES W. COTTEW, a citizen of the United States, residing at Sheridan, in the county of La Salle and State of Illinois, have invented a new and useful Combination Portable Elevator and Wagon-Dump, of which the following is a specification.

My invention relates to elevators for elevating grain and a device for dumping wagons; the two apparatuses combined together form a complete machine or device for dumping grain from a wagon and elevating it; and the objects of my improvements are, first, to provide means whereby the elevator and the wagon dump are driven at the same time from a common motor and the relative speed of the two can be changed while in motion; second, to make a universal wagon dumping device which is capable of being placed in any position relative to the elevator; third, to have the wagon dump connected to the source of power by a strut brace; fourth, to provide an adjustable receiving conveyer; fifth, to make a folding receiving conveyer; sixth, to make an automatic folding elevator; seventh, to automatically tighten and loosen the elevator belt when the elevator is extended and folded; eighth, to mount a hydraulic jack or suitable device on the elevator truck, to operate the wagon dump; ninth, to make a novel construction of truck for the elevator which will automatically allow the elevator boot to rest on the ground when the elevator is in a raised position; tenth, to enable the whole device to be loaded on a wheeled truck and to be set into operative position by one person; eleventh, to make a simple, cheap and durable construction and other objects to become apparent from the description to follow.

As is well known in the art, a wagon dump and an elevator are operated together as a complete device for conveying grain from a wagon to a grain bin or corn crib. Usually the front end of the wagon is raised, by suitable mechanism, to dump the grain out at the tail end of the wagon into a receiving conveyer, from whence it is conveyed into the elevator boot and thence carried up to its destination by the elevator. Heretofore motive power has been applied to run the elevator and hand power was ap-

plied to the wagon dump, which arrangement required several persons, to operate it. In some cases positive drive connection was arranged between the elevator and the wagon dump, but this proved to be inconvenient and impractical. Another feature of this class of machinery is that the loaded wagon has to be drawn into position with its rear end just above the receiving conveyer and its front wheels in position to be elevated by the wagon dump device. Heretofore this positioning of the wagon was accomplished either, by driving the wagon onto a turn-table immediately in front of the receiving conveyer and then turning the wagon on a pivot through an arc of ninety degrees, or, by first swinging the receiving conveyer about a pivot out of the path of the wagon and after the wagon is in position returning the conveyer to a position directly under the rear end of the wagon; these methods are both very inconvenient and require a considerable amount of muscular energy.

By the use of my invention the wagon dump is driven by the same motor which runs the elevator and is capable of having its speed of operation changed, to slower or faster, as desired, while the elevator continues to travel continuously at the same rate of speed; and to permit placing the wagon in proper position, the receiving conveyer has a pivoted section which is simply lifted to a vertical position to allow the wagon to pass by, and is then again lowered to the ground. It is often desirable to have the wagon in different positions relative to the elevator at different buildings or in different localities about the same building, and my invention makes it possible to arrange the receiving conveyer and wagon dump in any position about the elevator.

The wagon dumping device or lifting derrick is devoid of all shafts and gear wheels, so as to be light enough for a single person to handle; the lifting power is transmitted to it through a single cable or chain from a lifting device. This cable or chain is carried along on a jointed strut brace which permits the wagon dump to be placed in any position. The receiving conveyer is made with the upper or hopper part slideable longitudinally so as to enable moving it to a position directly under the wagon

box in case the wagon has through carelessness been placed slightly to one side or the other. The elevator is made of a plurality of sections jointed together and is provided at each joint with a sheave over which passes a cable, by means of which the several sections are folded on each other or extended, as desired, by manipulating the cables. When the elevator is folded, some provision must be made for slackening the conveying belt and this I accomplish by providing an automatic loosening and tightening device.

It is very desirable to have the wagon dumping device as light in weight as possible, since this part of the apparatus must be handled each time the elevator is set up at or removed from a given location. To accomplish this desired result I mount the power or lifting mechanism, which in this case is a hydraulic cylinder or jack, on the wheeled truck carrying the elevator; thus having only the plain derrick like structure to lift about in setting up or taking down the device.

Another desirable feature in elevators of this class is to have them mounted on a wheeled truck for transportation and to have the elevator boot rest firmly on the ground when the elevator is in operation, and by the use of my invention the elevator is automatically mounted on a wheeled truck when it is folded for transportation, and is similarly automatically dismounted from the front truck with the elevator boot resting on the ground when set up for elevating purposes. This result is obtained by a novel connection between the elevator and truck to be described.

It will be understood that in illustrating and describing my invention a complete device is shown to illustrate one construction embodying the new and novel features of my invention, and that numerous changes may be made in different parts of the machine without in the least departing from the spirit of the invention.

To describe my invention so that others versed in the art to which it pertains can make and use the same, I have illustrated it on the accompanying five sheets of drawings forming a part of this specification, in which:

Figure 1, is a side elevation of a device embodying my invention folded and mounted on a truck ready for transportation. Fig. 2, is a similar view but with the parts in position for operation. Fig. 3, is a plan view of the wagon dumping device. Figs. 4 and 5, are respectively a plan and side elevation of the strut bar connection forming a part of my invention. Figs. 6 and 7, are respectively a plan view and a longitudinal section on line 7-7 of Fig. 6, of the hydraulic jack; Fig. 8, is an enlarged side elevation of

the lower end of the elevator and the receiving conveyer, the latter being swung into a vertical position to permit the passage of a wagon. Fig. 9, is an inverted plan view of the pivoted truck of the elevator; Figs. 10, 11 and 12 are detail sectional views of the receiving conveyer; Figs. 13, 14, and 15 are detail views of the delivery end of the elevator showing the automatic tightening device for the conveyer belt, and Fig. 16, is a cross section on line 16-16 of Fig. 13.

Similar reference characters refer to similar parts throughout the several views.

Referring generally to Figs. 1, 2 and 3, 17 is the wagon dumping derrick, 18 is the jointed strut brace connecting the derrick 17 to the frame of the hydraulic jack 19. The wagon frame 20 is mounted on the front truck 21 and rear truck 22. The elevator 23 is pivotally mounted on the front end of the wagon frame 20 and is supported in its raised position by the masts 24 which are pivotally attached to the rear end of the wagon frame 20. 25 is the receiving conveyer operatively connected to the lower end of the elevator 23. The derrick 17 may be of any desired construction so long as it serves as a means for attaching a rope, cable, chain or bar in such manner that one end of a wagon can be lifted by exerting a pull on said rope, cable chain or rod. As an illustration, I have shown a cable 26 connected to two cables 27 and 28 which latter pass over small sheaves or idlers 29 and 30 in such position that the free ends of the cables 27 and 28 will hang down one on either side of a wagon placed under the derrick 17 as shown in Figs. 2 and 3, the position of the wagon being shown by dotted lines in Fig. 3. The free ends of the cables 27 and 28 are provided with loops 31 which are placed over the extending ends of the two front wheel hubs, and are prevented from slipping off of the same by the hooks 32 secured to the cables 27 and 28 each of said hooks being hooked around a spoke of the wheel. The free end of the cable 26 has preferably attached thereto a short piece of chain 33, and a hook 34 which is secured to the end of cable 35 is hooked into any desired link of the chain 33 to get the proper adjustment. The strut brace 18 may be of any desired construction, the essential features of it being to serve as a spanner to hold any two given objects separated against the tension of a pull between said points; which in this case are the derrick 17 and the hydraulic jack 19; said strut brace need not necessarily be jointed as the one shown. In the drawings, see Figs. 2, 3, 4 and 5, the strut brace 18 is composed of the two members 36 and 37 of which the one end of each are pivotally connected at 38. The free end of member 37 is provided with the perforated ears 39 which straddle the perforated and pivoted

ear 40 mounted on the derrick 17. A pin is passed through the perforations in the ears 39 and 40 which connects them pivotally. The ear 40 being pivoted to the derrick 17 and also pivoted to the ears 39 forms practically a universal joint between the strut brace 18 and the derrick 17. A roller or idler 41 is mounted on the free end of the member 37 and another idler 42 is mounted on the pivot 38. The idler 41 is mounted on the member 37 by means of a removable sleeve, which serves to make the idler 41 interchangeable. The free end of the member 36 is similarly provided with perforated ears 43 which straddle the perforated ear 44 secured to the hydraulic jack 19. A pin is passed through the perforations of ears 43 and 44 which pivotally connects them. The pins at either end of the strut brace 18 are made removable and the parts can be disconnected by removing the pins from their respective perforations. The cable 35 is passed under idlers 41 and 42 and has fastened to its ends, which extend a material distance beyond the ends of the strut brace 18, the hooks 34 and 46. The hook 46 is hooked to the moving part of a pulling or lifting mechanism which in this case is shown to be a hydraulic jack 19, but may be any other kind of hand or power mechanism capable of exerting the necessary pull. The hook 34 as above stated is hooked into any desired link of the chain 33. The hydraulic jack 19 is rigidly mounted in any suitable frame 47 which is pivotally secured to the wagon frame 20 at 48 to enable swinging its one end down to near the ground when the device is in an operative position. To secure the frame 47 in a tilted position with one end near the ground it is provided with two brace rods 49, preferably made adjustable in length, which have one end pivotally secured to frame 47 at 50 and the other end provided with a bent portion 51 to hook into or otherwise be secured to the eye or other device 52 on the wagon frame 20. A shaft 53 is rotatably mounted in frame 47 and has a sprocket wheel 54 secured to one end thereof which is connected by a chain 55 to an idler sprocket 56 which is made integral with the sprocket 57 (see Fig. 9) which is connected by a chain 58 to a sprocket 59 mounted on the driven shaft 60 journaled in the lower end of elevator 23. The shaft 60 may be driven by means of horse power or motor power. When driven by motor power and the motor is mounted on the wagon truck as indicated by dotted lines in Fig. 2, the power from the motor is applied preferably to the shaft 53 and thence the power is transmitted through sprocket 54, chain 55, sprockets 56 and 57, chain 58 and sprocket 59 to shaft 60. The shaft 53 is provided with an eccentric 61 which is connected by a pitman rod 62 to the piston rod 63 of a

pump 64. The outlet of the pump 64 is connected to one end of the cylinder 65 of the jack 19. Within the cylinder 65 is provided the usual piston which is secured to the rod 66 piercing the remaining end of the cylinder 65. Secured to the exposed end of rod 66 is the end piece 67, to which is secured one or more rods 68 which have their remaining end secured to a sliding piece 69, which is conveniently but not necessarily made in the shape of a ring to slide on the cylinder 65 as a guide. The sliding piece 69 is provided with means to which the hook 46 above referred to can be fastened.

From the description thus far given it is clear that the rotation of shaft 53 will operate pump 64 which will force the piston rod 66 out and pull the sliding piece 69 along on cylinder 65 in such manner as to cause a pull on the cable 35, which in turn transmits the pull to cables 27 and 28 which lift the wagon attached thereto.

It is preferable to use a liquid which will not freeze in the pump 64. The inlet of pump 64 is connected by a pipe 70 to the end of cylinder 65 remote from the pump 64, so that the liquid which is forced by the pump against one side of the piston within cylinder 65 is drawn from within the cylinder 65 but on the opposite side of the piston. A pipe 71 or other means of communication connects the end of cylinder 65, to which the pump 64 is connected with the pipe 70. The pipe 71 is provided with a valve or stop cock 72 by means of which the passage of liquid through the pipe 71 is controlled.

73 is a check valve at the inlet of the pump 64 arranged to permit the free passage of liquid into the pump and prevent any liquid from passing out of the pump. A similar check valve is of course provided between the pump 64 and cylinder 65 which permits the liquid to pass out of the pump and prevents the liquid from passing into the pump.

It is obvious that, by the system of connections and valves described, the wagon filled with grain can be raised or lowered or held stationary in any position while the shaft 53 rotates continually. When the valve or stop cock 72 is wide open the wagon will lower by force of gravity and will force the liquid ahead of the piston out of cylinder 65 through valve 72 and pipes 71 and 70 and into cylinder 65 on the rear side of the piston; and according to the degree of opening of valve or stop cock 72, *i. e.*, less or greater, the piston and therefore the wagon will move in one direction or the other or remain at rest. A rod of any desirable length may be attached to the handle of valve or stop cock 72, to bring it within easy reach of the operator.

The object of lifting the front end of the wagon is to dump the grain out of the rear

end of the wagon into the receiving elevator 23, which consists of the hopper portion 74 and the neck portion 75. The upper end of the neck 75 which lies in a horizontal plane is swivelly connected to a bracket 76 rigidly secured to the elevator 23 in such manner that the lower end of the neck 75 and the hopper portion 74 can be placed in any position radially about said swivel connection. Mounted on the bracket 76 is a shaft 77 which has secured to one end the sprocket wheel 78 which is connected by a chain to the sprocket wheel 59 referred to above. The chain 58 is conveniently run over the three sprocket wheels 78, 59 and 57 and the chain tightening idler 79 is mounted on the elevator 23 to bear against said chain 58.

An endless conveyer belt 80 (see Figs. 8 to 12), travels over wheels mounted on shaft 81 journaled in the upper horizontal end of the neck 75. The shaft 81 has secured to one end the sprocket wheel 82 which is connected by chain 83 to sprocket 84 mounted on shaft 85 also journaled in the upper horizontal end of neck 75. The shafts 85 and 77 are operatively connected by the usual train of gears mounted on the swivel connection referred to above.

The hopper portion 74 is pivotally connected to the neck portion 75 at 86 which is made in the form of a hinge extending the entire width of the elevator on the line of the floor of the upper inclined chute thus permitting the hopper portion 74 to be lifted up from its horizontal position about the pivot 86 until it reaches the position shown in Fig. 8. The two side wings 87 and 88 are pivotally secured to the rods 89 and 90 which are slidably mounted on the base or return chute 91. The pivoting of the wings 87 and 88 permits either wing to be swung down and out into the position shown in Figs. 11 and 12, so as to extend partly under the rear end of the wagon and prevent any grain from falling outside of the hopper. The longitudinal movement of the rods 89 and 90 permit the longitudinal movement of the hopper wings 89 and 88, so that these can be moved to a position directly under the rear end of the wagon, in case the wagon has carelessly been drawn slightly to either side of the proper position. A block or gate 92 is bolted in position to the front end of the wing which is swung under the wagon to prevent the grain from spilling out on the ground. The rear end of both wings 87 and 88 are provided with permanent end pieces 93 to prevent the grain from spilling onto the ground. The rods 89 and 90 are preferably made rigid to the end piece 94 forming the end of the hopper, and the front ends of said rods are rigidly connected together by the inverted U shaped standard or brace 95, which fits

between the upwardly extending sides 96 of the base 91. The upwardly extending sides 96 fit snugly against the inner sides of the side walls of the inclined portion of neck 75 to form a grain tight joint.

70 97 is a handle secured to the end piece 94, by which the hopper can be handled in lifting and sliding the same.

A chain 98 connects the rear ends of the wings 87 and 88 and a suitable link of the 75 same is fastened to a bolt 99 to support either wing in its position.

As seen in Figs. 2 and 8 to 12 the upper end of the neck 75 is horizontal while the balance and greater portion is on an incline 80 of about forty five degrees and joins the hopper portion which is normally in a horizontal position. The endless belt conveyer 80 as above described passes around the wheels on shaft 81, thence down the return 85 chute 100 of the neck 75, thence horizontally back in the return chute 91 of the hopper portion 74, thence around wheels on shaft 101 in the extreme rear end of said chute, thence horizontally forward in the 90 upper chute of the hopper portion 74, thence up in the upper chute of the neck 75 and again over the wheels on shaft 81. The corner shoes 102 are secured at the upward bend of the belt 80 to the side walls 96 95 for the purpose of holding the belt in proper position close to the floor of the upper chutes in hopper portion 74 and neck 75. It will be noted that the hinge or pivot 86 is so located with respect to the turning 100 points of the belt 80 that said belt is sufficiently slackened automatically to permit the folding of the receiving elevator 23 without disconnecting the belt.

The front truck 21 is provided with the 105 ordinary fifth wheel 103 and is connected to the wagon 20 in a novel manner. The upper structure of the fifth wheel 103 is provided with the cross bars or bolsters 104 and 105 extending across the entire width of 110 the elevator 23. A shaft 106 extends across on the under side of the elevator 23 and fixed to said elevator by passing through two lugs 107 shown by dotted lines in Fig. 9; this shaft 106 also passes through two 115 lugs 108 formed on either end of the bar 104 and through two bearing blocks 109 rigidly secured to the wagon 20, thus the upper portion of fifth wheel 103, the elevator 23 and the wagon 20 are connected 120 together by the shaft 106 which acts as a pivotal point about which they swing. The other bar 105 on the fifth wheel 103 has long lugs 110 formed one on each end thereof of which fit loosely against the sides of the 125 elevator 23, are curved on an arc about the shaft 106 as a center and are provided with the slots 111 into which fit the pins 112 rigidly secured to the elevator 23.

From the description thus far given it 130

will be seen that the elevator 23 can be lifted or turned upward in an arc about the shaft 106 as a pivot until the lower end of the elevator strikes the ground at which time the weight of the elevator is transferred from the truck 21 to the ground and said truck 21 and wagon 20 are relieved of the weight of the elevator. About the same time that the load is thus transferred to the ground the truck 21 will, partly by force of gravity and partly by the tendency of the elevator to slide back on the ground, be swung about the shaft 106 as a pivot away from the elevator 23 until said truck is barely supported on the ground and the pins 112 are in the ends of slots 111 remote from the fifth wheel 103. This is especially true when the elevator boot rests lower than the truck. The position of the pins 112 and the length of the slots 111 determine the extent of the arcuate movement of the truck 21 about the shaft 106. The idlers 56 and 57 above referred to are conveniently but not necessarily pivotally mounted on shaft 106.

The shaft 69 in the lower end of the elevator 23 carries the wheels which drive the endless belt conveyer to be described and to provide a means of access to these working parts, the elevator case is made with a removable section 113 secured at 114 and also fastened at 115.

The masts 24 at their lower ends are rigidly fastened to the rear axle 116, and a short distance above this they are pivotally secured to the wagon 20 at 117. A windlass 118 is fixed to the lower end of the masts 24, spanning the space between the masts, upon which is wound the ropes or cables 119 which pass from the windlass 118 upward over the idlers 120 at the top of the masts 24, thence down and secured to the elevator 23 at 121. The relative position of these several fastenings are such that, if a pull is exerted on cables 119 by operating the windlass 118, while the parts are in a folded position as seen in Fig. 1, the masts 24 will first be raised to the position shown in Fig. 2, and a further operation of the windlass 118 will lift the elevator 23 about its pivot, the shaft 106, into the position shown in Fig. 2. As a matter of fact, the masts 24 actually move to a vertical position before the elevator 23 starts to lift, and to prevent the masts 24 from falling over backward I provide the guy ropes 122 having one end secured to the front end of the wagon 20 and the remaining end of each rope secured to the masts 24 by means of the legs or standards 123 which as seen in Fig. 1, rests on brackets 124 secured to the wagon 20 when in its folded position. The lower ends of the standards 123 as also the brackets 124 are provided with perforations which register when the masts

are in a folded position, and into which is placed a bolt or pin to prevent the accidental displacement of the standards 123 during transportation. The purpose of providing the standards for the masts is to hang the derrick 17 thereon as seen in Fig. 1.

The elevator 23 comprises the four sections 125, 126, 127 and 128 which are hinged together at 129, 130 and 131. When extended they form a straight line elevator as seen in Fig. 2. Sections 125 and 126 are hinged together at 129, at which point the grooved wheels 132, one on either side of the elevator, are rigidly secured to the section 126. Sections 126 and 127, are hinged together at 130, at which point the grooved wheels 133, one on either side of the elevator, are rigidly secured to the section 127. Sections 127 and 128 are hinged together at 131 at which point the grooved wheels 134, one on either side of the elevator are rigidly secured to the section 128. Cables 135 extend around the grooved wheels 134 and from thence through guides on wheels 133 and 132 and finally around small sprocket wheels 136, mounted one on either side of section 125, the cables 135 at this place being a sprocket chain. The sprocket wheels 136 are rotated by some self-locking hand power means as a worm and gear 137. The cables 135 are secured against slippage on the wheels 134 by any means of clamping. When the sprocket wheels 136 are rotated non-clockwise as viewed in Fig. 2, the cables 135 will cause the wheels 134 to be rotated in the same direction and since the section 128 of the elevator is rigidly secured to the wheels 134 it will also be turned about the hinge 131 as a pivot until it is folded back onto the section 127 of the elevator. A reverse rotation of the sprocket wheels 136 will again swing the section 128 of the elevator out into its extended position as seen in Fig. 2. It is obvious that the purpose of mounting the wheels 136 and worms 137 on section 125 is to bring the operating crank within easy reach of a person operating the same. The worms 137 or an equivalent could be arranged to engage the wheels 134 and have the means of operating it extend along on the elevator to within easy reach of a person, without going beyond the bounds of the appended claims. Another pair of cables 138 one on either side of the elevator are passed around the grooved wheels 133, to which they are securely clamped and thence are passed idly past but lying in the grooves of the wheels 132 and thence to and around the sprocket wheels 139, mounted on section 125 of the elevator, the cables 138 at this portion being chains. The sprocket wheels 139 are rotated by some self-locking hand power means as a worm and gear 140. When the sprocket 130

wheels 139 are rotated non-clockwise as viewed in Fig. 2, the cables 138 will rotate the wheels 133 in the same direction and since the section 127 of the elevator is rigidly secured to the wheels 133 it will be swung about the hinge 130 as a pivot until the end 141 of section 128 (said section 128 having previously been folded down upon section 127) contacts with section 126. The further rotation of sprocket wheels 139 will by means of cables 138 and force of gravity, cause the section 126 to swing about hinge 129 as a pivot until the section 128 comes to rest on section 125 as seen in Fig. 1. The reverse movement of sprocket wheels 139 will by means of cables 138 first swing section 126 about pivot 129 until said section is in a position to form a straight line continuation of section 125, and then swing section 127 about pivot 130 until said section is in a straight line with sections 125 and 126 as seen in Fig. 2. A small idler 142 is provided on each wheel 132 to prevent the cables 138 from leaving the grooves of wheels 132 when the elevator is in a folded position.

An endless belt conveyer 143, see Figs. 14 to 16, passes up in the upper chute of the elevator 23 and down in the return chute of the same and is arranged to travel around wheels on drive shaft 59 and over wheels on shaft 144 mounted in the upper end of section 128. Since both strands of the endless belt conveyer 143 are on the same side of all the hinges of the elevator it is necessary to make some provision to slacken said belt conveyer 143 when folding the elevator, and I have made such provision by an automatically operated device. That is the shaft 144 is automatically moved in a direction away from the end 141 when the section 128 is swung about pivot 131 from the position shown in dotted lines in Fig. 13, to the full line position in said Fig. 13. The shaft 144 is mounted in the bearing plates 145 rigidly secured to the outer sides of the box like frame 146 which is mounted to slide between the bottom of the return chute and the bottom of the upper chute of the elevator. As shown in the drawings the box like frame 146 is confined within the sides of the return chute but has its sides fitting snugly against the outer surfaces of the upper chute of the elevator, thus preventing any possible leakage of grain at this point. To rigidly secure the return chute and the upper chute together the bent braces 147 are provided on either side.

The box like frame 146 is held in position longitudinally by the two side bars 148 each of which have one end pivoted to frame 146 at 149 and the remaining end pivoted to the arm 150 which are loosely pivoted concentric with the hinge 131. Adjustable set screws 151 are provided in suitable lugs 65 on section 127 of the elevator which serve

as stops for the arms 150. As seen in Fig. 13, when the section 128 is in its extended position, *i.e.* in a straight line with section 127 as indicated by dotted lines, the arms 150 are resting against the set screw 151 and by means of the bars 148 the box like frame 146 and therefore the shaft 144, are moved to the limit of their movement in the direction toward the end 141, thus tightening the endless conveyer belt 143. To enable taking up the slack in the belt 143 occasioned by wear the set screws 151 are made adjustable. It is also seen in Fig. 13, that when section 128 is moved from its extended position to a partly folded position, as the full line position the frame 146 is permitted to move in a direction away from the end 141 thus slackening the belt 143. The upper side 152 of the frame 146 is made of wood and is covered with sheet metal 153 which is bent in a cylindrical form about the shaft 144 and its extremity turned and secured to the under side of the wood board 152. The metal covering 153 serves as an extension of the bottom of the upper chute and also prevents any grain from falling any place besides out at the discharge end of the elevator.

As seen in Fig. 1, the complete apparatus is conveniently folded on the wagon in a compact form. The main upright frames of the derrick 17 are hung on the hooks 154 provided on the masts 24.

Having thus fully described my invention what I claim as new and desire to secure by Letters Patent of the United States is:

1. In a device of the class described, an elevator, a wagon dump, means mounted on the elevator whereby said elevator and said dump are operated simultaneously from a common motor and means mounted on the elevator for varying the speed at which the dump moves with relation to the speed at which the elevator moves while both the elevator and the dump are operating.

2. In a device of the class described, a truck provided with four traction wheels, an elevator mounted on said truck, a wagon dumping device comprising a derrick and a rope or cable separate and disconnected from said truck capable of being positioned at any angle to said elevator and means mounted on said truck to exert a pull on said rope or cable.

3. In a device of the class described, a truck, a wagon dump separate and disconnected from said truck comprising a derrick and a rope or cable, means mounted on said truck for exerting a pull on said cable and a brace connecting said derrick and said pulling means along which said rope or cable extends.

4. In a device of the class described, a cable pulling mechanism, a wagon dumping device comprising a cable to operate the

same, a coupling cable connecting the said pulling mechanism and the cable on said dumping device and a jointed strut brace having one end flexibly connected to said pulling mechanism and the other end flexibly connected to said dumping device.

5. In a device of the class described, a truck or wagon, an elevator mounted on said truck, a wagon dumping device separate and disconnected from said truck comprising a cable, a cable pulling device mounted on said truck and a brace connecting said dumping device and said pulling device along which the cable extends.

15. 6. In a device of the class described, a wagon dump, a cable pulling device, a cable or rope, connecting said wagon dump and said cable pulling device and a strut brace detachably connected to said wagon dump and said pulling device along which said cable extends.

7. In a device of the class described, a truck or wagon, an elevator mounted on said truck, a wagon dumping device separate and disconnected from said truck comprising a cable, a cable pulling device comprising a pump and a hydraulic cylinder mounted on said truck, and a brace connecting said dumping device and said pulling device along which the cable extends.

35. 8. In a device of the class described, a portable truck, a wagon dump comprising devices for engaging the front end of a wagon separate and disconnected from said truck capable of being positioned at any desired angle to the truck, a liquid pressure cylinder and piston mounted on the truck, a pump mounted on the truck arranged to force liquid into said cylinder, 40 flexible connecting means whereby proper movement of the piston lifts the wagon and valve controlled means for discharging liquid from the cylinder.

9. In a device of the class described, a 45 portable truck, a portable wagon dump separate and disconnected from said truck capable of being positioned at any angle to said truck for operation, a hydraulic pump mounted on said truck, and means in connection therewith for operating the wagon dump, means for automatically interrupting the raising movement of the wagon, and other means for permitting the wagon and its raising means to lower independent 65 of the pumping means.

10. In a device of the class described, a 60 portable truck, a wagon dump separate and disconnected from said truck arranged capable of being positioned at any desired angle to the truck, a continuously acting hydraulic pump mounted on said truck and means in connection therewith for operating the wagon dump, means for automatically interrupting the raising movement of the wagon and other means for permitting the 65

wagon to lower independent of the said pumping means.

11. In a device of the class described, a portable truck, a portable wagon dump separate and disconnected from said truck arranged capable of being positioned for operation at any desired angle to said truck, hydraulic means mounted on said truck for operating the wagon dump, means for arresting the upward movement of the wagon independent of the movement of said hydraulic means and other means for permitting the wagon to lower at a faster speed than that at which it is raised.

12. In a device of the class described, a 80 portable truck, a portable wagon dump, comprising lifting means for the wagon separate and disconnected from said truck capable of being positioned at any desired angle to said truck for operation, means 85 mounted on the truck operated by hydraulic pressure for operating the wagon dump, means in connection with said pressure means for automatically arresting the upward movement of the wagon and other 90 means also in connection with the pressure means for causing the wagon to be lowered.

13. In a device of the class described, a truck or wagon, an elevator mounted on said truck or wagon, means on the truck or 95 wagon to support the elevator in an inclined position for operation, means on the truck or wagon to retain the elevator in a folded or packed condition for transportation, a wagon dumping derrick separate and disconnected from said truck arranged to be operatively connected to said elevator and means on the truck for retaining the derrick in a knocked down or packed condition for transportation.

100 14. In a device of the class described, an elevator and a receiving elevator comprising a hopper portion and a neck portion swivelly connected to said elevator, said hopper portion pivoted to said neck portion 110 to swing on a horizontal axis, a wagon dump, means mounted on the elevator whereby said elevators and said dump are operated simultaneously from a common motor and means mounted on the elevator 115 for varying the speed at which the dump moves with relation to the speed at which the elevators move while both elevators and the dump are operating.

15. In a device of the class described, an 120 elevator comprising a plurality of hinged members or sections, a mast to raise the elevator, means whereby first the mast and then the elevator are raised from a common source of power, a wagon dump, means 125 mounted on the elevator whereby said elevator and said dump are operated simultaneously from a common motor and means mounted on the elevator for varying the speed at which the dump moves with rela- 130

tion to the speed at which the elevator moves while both the elevator and the dump are operating.

16. In a device of the class described an elevator comprising a plurality of sections hinged together and means operated by a crank on the lower section secured at each hinge whereby the different sections can be folded and extended, a wagon dump, means mounted on the elevator whereby said elevator and said dump are operated simultaneously from a common motor and means mounted on the elevator for varying the speed at which the dump moves with relation to the speed at which the elevator moves while both the elevator and the dump are operating.

17. In a device of the class described, an elevator comprising a plurality of sections hinged together and an endless conveyer belt, means whereby the conveyer belt is automatically slackened when the elevator is folded and automatically tightened when the elevator is extended, a wagon dump, means mounted on the elevator whereby said elevator and said dump are operated simultaneously from a common motor and means mounted on the elevator for varying the speed at which the dump moves with relation to the speed at which the elevator moves while both the elevator and the dump are operating.

18. In a device of the class described, an elevator comprising a plurality of sections hinged together and means secured at each

hinge whereby the different sections can be folded and extended, a wagon dump, means mounted on the elevator whereby said elevator and said dump are operated simultaneously from a common motor and means mounted on the elevator for varying the speed at which the dump moves with relation to the speed at which the elevator moves while both the elevator and the dump are operating.

19. In a device of the class described, an elevator comprising a plurality of sections hinged together and an endless conveyer belt, and means mounted on the uppermost section whereby the conveyer belt is automatically slackened when the uppermost section is folded on its hinge and is automatically tightened when said uppermost section is extended, a wagon dump, means mounted on the elevator whereby said elevator and said dump are operated simultaneously from a common motor and means mounted on the elevator for varying the speed at which the dump moves with relation to the speed at which the elevator moves while both the elevator and the dump are operating.

In testimony whereof I have signed my name to this specification in presence of two subscribing witnesses this 5th day of March 1908 at Chicago, Illinois.

CHARLES W. COTTEW.
